UNITED STATES PATENT OFFICE

2,212,198

TRANSFORMER OF THE CONSTANT OR
LIMITED CURRENT TYPEJoseph G. Sola, Oak Park, Ill., assignor to Sola
Electric Co., Chicago, Ill., a corporation of
Delaware

Application March 25, 1940, Serial No. 325,720

10 Claims. (Cl. 171—119)

My invention relates to an improved transformer arrangement of the constant or limited current type. My invention in certain respects is related to the transformer arrangements shown and described in my Patent No. 2,143,745, issued January 10, 1939.

It is an object of my invention to provide an improved transformer arrangement of the type having a constant or limited output current characteristic and which with any certain load has an output current that remains substantially constant irrespective of variations of the primary or input voltage to the arrangement.

It is another object of my invention to provide an improved transformer arrangement of the type having a constant or limited output current characteristic, the efficiency and power factor of which are high while the temperature rise of the magnetic core is low.

It is a further object of my invention to provide an improved transformer arrangement of the type having a constant or limited output current characteristic and which comprises a single unit and may be economically manufactured.

It is also an object of my invention to provide an improved transformer arrangement of the type having a constant or limited output current characteristic and which comprises two windings loosely coupled together magnetically and a condenser, one of the windings being a load winding and the other being a primary winding with respect to the load winding and forming with the condenser a resonant circuit.

The invention consists of the novel constructions, arrangements, and devices to be herein-after described and claimed for carrying out the above stated objects and such other objects as will appear from the following description of certain preferred embodiments illustrated in the accompanying drawings, wherein,

Fig. 1 is a transformer unit embodying the principles of my invention;

Fig. 2 is a diagrammatic illustration of one form of wiring arrangement that may be used with the transformer unit shown in Fig. 1;

Figs. 3, 4 and 5 are diagrammatic illustrations of modified forms of transformer arrangements, embodying the principles of my invention, that may be used with magnetic cores such as that of the transformer unit shown in Fig. 1; and

Figs. 6 and 7 are graphs showing the operating characteristics typical of transformers embodying my improvements.

Like characters of reference designate like parts in the several views.

Referring to Figs. 1 and 2, it will be seen that a core type of transformer construction is illustrated, the closed magnetic circuit 10 of which comprises a stack of I-shaped laminations forming a straight core bar 11 and a stack of laminations which form a magnetic return path 12 in the form of an inverted U or yoke disposed with its end legs 12a in abutting relation with 10 the core bar 11. The laminations may be held together by any suitable means.

On the end portion A of the core bar 11, I have provided a primary or input winding 13, the terminals 14 and 15 of which are adapted to be connected with a source of alternating current, the voltage of which from time to time may fluctuate or vary substantially. On the central portion B of the core bar 11, I have mounted what may be termed an intermediate winding 16, which is in spaced relation to but magnetically coupled with the winding 13, the winding 16 having terminal leads 17 and 18. A condenser 19 is connected between the leads 17 and 18 and thereby across the winding 16 for purposes hereinafter to be described. On the end portion C of the core bar, I have mounted a winding 20 having terminal leads 21 and 22. The winding 20 may be termed a load winding and is spaced from but is magnetically coupled with the winding 16.

The magnetic circuit 10 is provided with a high leakage reactance path 12b between the windings 13 and 16 and a high leakage reactance path 12c between the windings 16 and 20. The paths 12b and 12c comprise central, inwardly extending legs of the magnetic return path 12 which terminate short of the core bar 11 thereby providing non-magnetic or air gaps 23. The paths 12b and 12c are magnetically permeable shunts, each having a non-magnetic gap portion, and are so arranged that magnetic flux may thread each of the windings 13, 16 and 20 to the exclusion of the other windings.

The transformer arrangement shown in Fig. 3 is provided with a magnetic core similar to the core of the Fig. 1 arrangement. In this Fig. 3 arrangement, the load winding 20 is connected by its terminal lead 21a in series with an auxiliary winding 24 having a terminal lead 25, the winding 24 being wound on the portion A of the core bar 11 and closely coupled magnetically with the input winding 13.

The transformer arrangement of Fig. 4 also comprises a magnetic core similar to that of 55

the Fig. 1 transformer. In this Fig. 4 arrangement, the windings 13 and 16 are connected together with an auto type of connection, the condenser 19 being connected between the leads 18 and 14 and across the windings 13 and 16, and the lead 17 is connected to the lead 15, thereby connecting the windings 13 and 16 in series. In other respects, the wiring arrangement is similar to that of Fig. 3.

- 10 The transformer arrangement shown in Fig. 5 may also comprise a magnetic core and windings similar to the Fig. 1 transformer. In this Fig. 5 arrangement, however, the windings 13 and 16 are connected together with an auto type of connection, and the winding 16 is also connected to the winding 20 with an auto type of connection. The condenser 19 is connected between the leads 18 and 14 and across the windings 13 and 16, and the lead 17 is connected to the lead 15, thereby connecting the windings 13 and 16 in series. The winding 20 is connected with the winding 16 by the terminal lead 21b which is connected to an intermediate tap 26 of the winding 16.

- 23 In my several transformer arrangements, V_p represents the voltage applied across the input or primary windings 13; V_i represents the voltage across the intermediate windings 16; V_L represents the voltage across the load windings 20; and V_o represents the output voltages; V_o and V_L being the same in the Fig. 2 arrangement. In the arrangements of Figs. 3 and 4, V_A represents the voltage across the auxiliary windings 24.

35 The principles upon which my improved transformers operate will be clear from a detailed consideration of the arrangement shown in Figs. 1 and 2. A voltage V_p from an external source is applied across the primary winding 13 causing current to flow through the winding 13 setting up magnetic flux in the core portion A. The windings 13 and 16 are magnetically coupled and the flux set up in the core portion A makes a circuit through the core bar 11 and magnetic return path 12 and links the winding 16. This 40 flux causes a definite reaction and voltage to be set up in the winding 16. As the voltage V_p on the primary winding 13 is increased from zero to a higher level, the flux threading the winding 16 tends to increase in nearly direct proportion to 45 the primary flux. Due to the reluctance of the air gaps 23, only a slight amount of flux leaks through the shunts 12b and 12c. As the induced E. M. F. reaches a higher value in winding 16, a critical point is reached where resonance takes 50 place, and then the reactance of the effective inductance of the winding 16 and the capacity reactance of the condenser 19 are approximately 55 equal, that is to say,

$$60 \quad 2\pi fL = \frac{1}{2\pi fC}$$

where f is the frequency of the voltage impressed on the primary winding 13, L is the effective inductance of the winding 16 and C is the capacity of the condenser 19. Under this resonant condition, a definite amount of current will flow in the resonant circuit, comprising the winding 16, condenser 19 and leads 17 and 18; and such current will be limited by the constants of that circuit, 70 and the result is that a potential V_i will be set up across the winding 16 and a corresponding amount of magnetic flux will be set up in the center portion B of the core bar 11.

75 When the circuit comprising the winding 16 and the condenser 19 is in resonance, the mag-

netic density of the core portion B is greater than the magnetic density in the core portion A. As the voltage V_p on the winding 13 is increased, the magnetic flux density in the core portion A increases, but the magnetic density in the core portion B stays substantially the same and increases only slightly since more and more flux is by-passed through the shunt 12b. The voltage V_i across the winding 16 also stays substantially the same and increases only slightly with a corresponding slight increase of magnetic flux density in the core portion B. Due to the passage of flux, created by the flow of current in the primary winding 13, through the shunt 12b to the exclusion of winding 16, the coefficient of coupling 15 between the primary winding 13 and the intermediate winding 16 is at a reduced value, and a balanced condition is maintained as the voltage V_p is varied in a range above its critical value such that the resonant circuit will continue to 20 oscillate with substantially a maximum current therein at a frequency equal to the frequency of the voltage impressed on the primary or input winding 13.

When the winding 20, which is magnetically coupled with the winding 16, is open and has no load connected between its terminals 21 and 22 substantially all the magnetic flux in the core portion B also threads the portion C of the core, and substantially none of the magnetic flux in 30 the portion B passes through the shunt 12c. However, when a load, such as a gaseous discharge tube 21, is connected between the terminals 21 and 22 of the winding 20, the magnetic flux density in the core portion C decreases. 35 Some of the magnetic flux in the core portion B now passes through the shunt 12c to the exclusion of winding 20. The voltage V_o , therefore, with the load 27 between the terminals 21 and 22 is less than the voltage V_o with no load between 40 said terminals. With a load current flowing in the winding 20, there is a tendency for the magnetic flux density in the core portion B and the voltage V_i to decrease from their no load values since the windings 16 and 20 are magnetically 45 coupled and the load on winding 20 is reflected to the resonant circuit. However, the arrangement is such that on the application of a load across the winding 20, more current flows through the primary winding 13, and the net 50 result is that the magnetic flux density in the core portion B and the voltage V_i remain substantially the same.

A load of substantially any impedance or one which varies in impedance may be put between 55 the terminals 21 and 22 of the winding 20, and the terminals 21 and 22 may even be shorted together without an excessive flow of current in the winding 20. The magnetic flux in the core portion B either passes through the shunt 12b, 60 to the exclusion of the winding 20, or else threads the winding 20. That portion of the magnetic flux passing through the shunt 12c produces a self-inductive effect in the winding 16, while the flux which passes through the core portion C 65 and through the winding 20 results in the production of secondary current in the winding 20. Any tendency to increase the load current in the winding 20 will at once be followed by increased self-induction of the winding 20 due to the increased flow of magnetic flux from the winding 20 through the shunt 12c, and at the same time the self-induction of the winding 16 will also increase owing to the increased amount of flux from the winding 16 flowing through the shunt 70 75 75

12c. The effect of the increased self-induction of winding 20 due to an increase in current in the winding is to choke or turn back the magnetic flux lines tending to pass through the winding 20 from the winding 16 and to cause these flux lines to be shunted through the shunt 12c. A varying impedance in the circuit of the load winding 20, therefore, receives a current which tends to be limited in strength and to be self-regulated. When there is a high impedance load between the terminals 21 and 22 of the winding 20 nearly all the magnetic flux in the core portion B passes through the winding 20 and the voltage V_o is at a high value but when the impedance of the load is decreased substantially such that a much larger load current would flow with the same V_o , then a much smaller portion of the magnetic flux threading the winding 16 passes through the winding 20 and the voltage V_o , therefore, decreases substantially such that the load current remains the same or only rises slightly. When the leads 21 and 22 are shorted together the voltage V_o is substantially zero, but the current through the winding 20 either remains constant or increases only slightly since most of the flux passing through each of the windings 16 and 20 passes through the shunt 12c to the exclusion of the other winding. With this arrangement there is no danger of an excessive flow of current through the winding 20 causing it to burn out.

In short, the winding 13 operates as a primary winding with respect to the winding 16 and, due to the presence of the shunt 12b between them, the windings 13 and 16 are loosely coupled together, and the circuit comprising the winding 16 and the condenser 19 resonates at the frequency of the voltage V_p applied to the input winding 13 when the voltage V_p is above a certain critical value. The winding 16 operates as a primary winding with respect to the winding 20, and, when there is no load between the terminals 21 and 22 of the winding 20, the magnetic coupling between the windings 16 and 20 is substantially unity, but when a decreasing load is present between the terminals 21 and 22 tending to cause an increasing flow of current in the winding 20 the magnetic coupling between the windings 16 and 20 decreases. The voltage V_i across the winding 16 remains substantially the same regardless of the load between the terminals 21 and 22 of the winding 20 and the voltage V_i increases only slightly with an increase of V_p ; the winding 16 is in effect then a constant voltage primary winding with respect to the winding 20.

In the Fig. 3 arrangement, an auxiliary winding 24 closely coupled with the primary winding 13 is connected in series with the load winding 20. As has been noted heretofore the voltage V_i increases slightly upon an increase of voltage V_p , and V_L and V_A also increase. With the auxiliary winding 24, substantially no increase of current through or voltage across a constant load between the leads 22 and 25 will take place upon an increase of the voltage V_p . The number of turns in the winding V_A is such that, upon an increase of voltage V_p , the vectorial difference between the voltages V_L and V_A stay substantially the same and this voltage difference is the voltage V_o ; and since V_o is constant, the current flowing through the load 27 also remains substantially the same.

In the Fig. 4 arrangement, the voltage V_p is impressed across both windings 13 and 16, and the winding 16 is caused to resonate not only by

the magnetic flux from the winding 13 but also due to the voltage V_p impressed across the winding 16.

In the Fig. 5 arrangement, the winding 16 is caused to resonate as in Fig. 4 arrangement and the output voltage V_o taken between the leads 18 and 22 is the sum of the voltage V_L across the winding 20 and the voltage across that portion of the winding 16 between the leads 18 and the tap 26.

The graph in Fig. 6 shows the manner in which the input power factor and the load current of a certain embodiment of my Fig. 3 transformer arrangement varies with the input voltage V_p , the load being substantially constant and of unity power factor. It will be noted that the input power factor is substantially unity and that the load current is substantially constant as V_p increases. The graph in Fig. 7 shows the manner in which the output voltage V_o of the embodiment aforesaid decreases with a constant V_p on a decrease of load impedance as the output current increases to a limit or constant value, the limit in this case being 4 amperes at short circuit of leads 22 and 25. Results approximating those shown in the graphs of Figs. 6 and 7 are obtained with the other forms of my invention described herein.

My improved transformer arrangements are of the high reactance type and are particularly suitable for use with mercury vapor lamps, neon electric discharge tubes, or other loads having a negative resistance characteristic. My transformer arrangements constitute electric supplies which substantially decrease in output voltage on the passage of an increased amount of current from the arrangements to their loads, this being the type of electric supply required to operate satisfactorily loads having a negative resistance characteristic, and my transformer arrangements are such that variations of input voltage to the arrangements have substantially no effect on the voltage across or the current through the loads. Each of my improved transformer arrangements consists of only a single unit which may be economically manufactured. The temperature rise in the magnetic cores of my arrangements is low, and the efficiency thereof is high.

I wish it to be understood that my invention is not to be limited to the specific constructions shown and described, except so far as certain of the claims may be so limited, as it will be apparent to those skilled in the art that changes in the constructions and arrangements may be made without departing from the principles of my invention.

I claim:

1. In a transformer of the type described, the combination of a magnetic core having thereon an input winding adapted to be connected to a source of alternating current of fluctuating voltage, an intermediate winding on said core magnetically coupled with said input winding, a load winding on said core magnetically coupled with said intermediate winding, said core providing high leakage reactance paths magnetically between said windings for flux to thread through each of the windings to the exclusion of the other windings, and a condenser connected across at least said intermediate winding and forming therewith a resonant circuit for maintaining the voltage across the intermediate winding substantially constant, said load winding serving as a limited current supply.

2. In a transformer of the type described, the combination of a magnetic core having thereon an input winding adapted to be connected to a source of alternating current of fluctuating voltage, an intermediate winding on said core magnetically coupled with said input winding, a load winding on said core magnetically coupled with said intermediate winding, said core providing a magnetically permeable shunt magnetically between said input and intermediate windings and a magnetically permeable shunt magnetically between said intermediate and load windings, each of said shunts having a non-magnetic gap portion, and a condenser connected across at least said intermediate winding and forming therewith a resonant circuit for maintaining the voltage across the intermediate winding substantially constant, said load winding serving as a limited current supply.
3. In a transformer of the type described, the combination of a magnetic core having a straight core portion, an input winding on said core portion adapted to be connected to a source of alternating current of fluctuating voltage, a load winding on said core portion, an intermediate winding on said core portion between the input and load windings, said core providing high leakage reactance paths between said windings for flux to thread through each of the windings to the exclusion of the other windings, and a condenser connected across at least said intermediate winding and forming therewith a resonant circuit for maintaining the voltage across the intermediate winding substantially constant, said load winding serving as a limited current supply.
4. In a transformer of the type described, the combination of a magnetic core having a straight core portion, an input winding on said core portion and adapted to be connected to a source of alternating current of fluctuating voltage, a load winding on said core portion, an intermediate winding on said core portion between the input and load windings, said core providing between said input and intermediate windings and between said intermediate and load windings magnetically permeable shunts each having a non-magnetic gap portion, and a condenser connected across at least said intermediate winding and forming therewith a resonant circuit for maintaining the voltage across the intermediate winding substantially constant, said load winding serving as a limited current supply.
5. In a transformer of the type described, the combination of a magnetic core having thereon an input winding adapted to be connected to a source of alternating current of fluctuating voltage, an intermediate winding on said core magnetically coupled with said input winding, a load winding on said core magnetically coupled with said intermediate winding, said core providing high leakage reactance paths magnetically between each of the windings to the exclusion of the other windings, a condenser connected across at least said intermediate winding and forming therewith a resonant circuit for maintaining the voltage across the intermediate winding substantially constant, and an auxiliary winding closely coupled magnetically with said input winding and connected in series with said load winding and serving with the load winding as a limited current supply.
6. In a transformer of the type described, the combination of a magnetic core having thereon an input winding adapted to be connected to a source of alternating current of fluctuating voltage, an intermediate winding on said core magnetically coupled with said input winding, a load winding on said core magnetically coupled with said intermediate winding, said core providing high leakage reactance paths magnetically between each of the windings to the exclusion of the other windings, and a condenser connected across at least said intermediate winding and forming therewith a resonant circuit for maintaining the voltage across the intermediate winding substantially constant, said load winding being connected with said intermediate winding and serving with said intermediate winding.
7. In a transformer of the type described, the combination of a magnetic core having a straight core portion, an input winding on said core portion adapted to be connected to a source of alternating current of fluctuating voltage, a load winding on said core portion, an intermediate winding on said core portion between the input and load windings, said core providing high leakage reactance paths between said windings for flux to thread through each of the windings to the exclusion of the other windings, a condenser connected across at least said intermediate winding and forming therewith a resonant circuit for maintaining the voltage across the intermediate winding substantially constant, and an auxiliary winding on the core in inductive relation to said input winding and connected in series with said load winding and serving with the load winding as a limited current supply.
8. In a transformer of the type described, the combination of a magnetic core having thereon an input winding adapted to be connected to a source of alternating current of fluctuating voltage, an intermediate winding on said core connected with and magnetically coupled with said input winding, a load winding on said core magnetically coupled with said intermediate winding, said core providing high leakage reactance paths magnetically between said windings for flux to thread through each of the windings to the exclusion of the other windings, and a condenser connected across said intermediate winding and across at least a portion of said input winding and forming with the intermediate winding and the connected portion of the input winding a resonant circuit for maintaining the voltage across the intermediate winding substantially constant, said load winding serving as a limited current supply.
9. In a transformer of the type described, the combination of a magnetic core having thereon an input winding adapted to be connected to a source of alternating current of fluctuating voltage, an intermediate winding on said core magnetically coupled with said input winding, a load winding on said core magnetically coupled with said intermediate winding, said core providing high leakage reactance paths magnetically between said windings for flux to thread through each of the windings to the exclusion of the other windings, and a condenser connected across at least said intermediate winding and forming therewith a resonant circuit for maintaining the voltage across the intermediate winding substantially constant, said load winding being connected with said intermediate winding and serving with said intermediate winding.

the connected portion of the intermediate winding as a limited current supply.

10. In a transformer of the type described, the combination of a magnetic core having thereon an input winding adapted to be connected to a source of alternating current of fluctuating voltage, an intermediate winding on said core connected with and magnetically coupled with said input winding, a load winding on said core magnetically coupled with said intermediate winding, said core providing high leakage reactance paths magnetically between said windings for flux to thread through each of the windings to
- the exclusion of the other windings, and a condenser connected across said intermediate winding and across at least a portion of said input winding and forming with the connected portion of the input winding and the intermediate 5 winding a resonant circuit for maintaining the voltage across the intermediate winding substantially constant, said load winding being connected with said intermediate winding and serving with the connected portion of the intermediate winding as a limited current supply. 10

JOSEPH G. SOLA.
